Specification for Design.

Patented Sept. 6, 1921.

Application filed January 28, 1921. Serial No. 440,816. Term of patent 3½ years.

To all whom it may concern:

Be it known that I, ALBERT R. ZWEBELL, a citizen of the United States, residing at Milwaukee, in the county of Milwaukee and State of Wisconsin, have invented a new, original, and ornamental Design for Automobile-Bodies, of which the following is specification, reference being had to the accompanying drawing, forming part thereof.

Figure 1 is a perspective view showing

the side of the body which is provided with a door.

Fig. 2 is a side elevation of the body showing the side opposite to that shown in Fig. 1.

Fig. 3 is a plan view.

I claim:

The ornamental design for an automobile body, as shown.

ALBERT R. ZWEBELL.
